UNITED STATES PATENT OFFICE.

T. L. MELONE, OF GRANVILLE, OHIO.

IMPROVEMENT IN SEWING-MACHINES.

Specification forming part of Letters Patent No. 44,332, dated September 10, 1864.

To all whom it may concern:

Be it known that I, T. L. MELONE, of Granville, in the county of Licking and State of Ohio, have invented certain new and useful Improvements in Sewing-Machines; and I do hereby declare that the following is a full, clear, and exact description thereof, which will enable others skilled in the art to make and use the same, reference being had to the accompanying drawings, forming part of this specification, in which—

Figure 1 is a vertical section of a machine with my improvements, taken at right angles to the shuttle-race and parallel with the needle-arm. Fig. 2 is a plan of the same with the cover of the shuttle-race removed. Fig. 3 is a left-hand side view of the shuttle-race and feeding-dog.

Similar letters of reference indicate like parts.

The principal object of my invention is to simplify and reduce the cost of the shuttle sewing-machine.

It consists in a novel construction an arrangement of the mechanism for operating the needle, the shuttle, and the feeding device, whereby the number of the parts of the machine is reduced, its construction simplified, and the machine enabled to be driven with less power.

It also consists in making the shuttle-race and feed-bar of one piece, or, in other words, in the employment, for feeding the material to be sewed, of a longitudinally-movable shuttle-race, thereby reducing the number of parts of the machine.

A is the cloth-bed of the machine, on which the material is to be placed to be sewed. Below this bed the driving-shaft B is arranged in an upright position directly under the shuttle-driver and near the middle of the shuttle-race, the said shaft being supported at the bottom on a center bearing, a, and working also in a guide-bearing, b. On this shaft there are firmly secured the band-wheel C, the needle-operating cam D, the fly-wheel E, and the feed-cam F, all so close together that they may be combined in a single casting, in the top of which is secured the eccentric wrist or crank-pin e for operating the shuttle-driver. Owing to the arrangement of the main shaft B, as above described, the end of the arm G

of the said lever to which the needle is attached, and the end of the arm H, by which motion is received from the arm D, both have to be on one side of the rock-shaft d, to which the said lever is secured, and one arm has to be over the other; and in order to balance the said lever, or prevent all its weight from coming on one side of the said rock-shaft, the connection of the said arms is extended in the form of a bow on the opposite side of the said rock-shaft, as shown at I in Fig. 2, by which means the necessity for lifting the whole weight of the said arms to raise the needle is obviated, and the machine is enabled to work more easily and steadily and with less labor on the part of the operator.

The shuttle-driver J is substantially of the usual construction. It is fitted to slide freely parallel with the raceway and feed-motion on a stationary horizontal bar, k, secured below the-cloth bed A, directly over the shaft B, and has firmly secured to it a slotted yoke, c, which receives the crank or eccentric wrist-pin e. The form of the slot in this yoke is such that the said pin e, working in it, will produce the desired movement of the shuttle.

L is the shuttle-race, made substantially of the usual form, and arranged in the usual position; but, instead of being stationary, it is fitted to slide longitudinally in or attached to the cloth-bed A a distance equal to the greatest length of feed required. The shuttle-race thus arranged serves also as the feed-bar. It has applied to it a spring, f, which tends to press it back in the opposite direction to the feed movement, and a stop-screw, g, which limits the point to which it is pressed back by the said spring. This spring and stop-screw are substantially like the spring and stop-screw commonly applied to the feed-bar.

h is the feed-dog, pivoted to the shuttle-race by a pin, i, as shown in Figs. 2 and 3, to permit it to rise and fall freely within the opening provided for its reception in the cloth-bed. The shuttle-race and dog thus applied combine to form what is known as the "four-motion" or "square" feed.

The feed-cam F is a double cam, its upper face being formed to produce the upward movement of the feed-dog to make it bite the cloth, and its peripheral surface operating upon an arm, j, rigidly secured to the shuttle-

race, to produce the longitudinal movement of the shuttle-race, by which the feeding of the cloth is effected.

In consequence of the longitudinal movement given to the shuttle-race, the width of the grooves *kl* provided therein for the reception of the needle and the loops of the needle-thread requires to be as much greater than the width of the needle as the length of the said longitudinal movement.

The band-wheel *C*, needle-operating-cam *D*, fly-wheel *E*, and feed-cam *F*, instead of being made of a single casting, as described, may be made of separate pieces; but I prefer to make them all of one casting, as a great saving of labor is thereby effected.

What I claim as my invention, and desire to secure by Letters Patent, is—

1. The main driving-shaft *B*, arranged vertically below the shuttle-driver and near the raceway, and in relation to the needle-arm and shuttle-driver substantially as herein specified, the same containing thereon, and the whole cast in one piece, the band-wheel, needle-operating cam, fly-wheel, and feed-cam, substantially as herein specified.

2. The employment, for feeding the material to be sewed, of a feeding-dog, attached to and receiving its forward and back movements from a reciprocating shuttle-race, substantially as and for the purpose herein specified.

T. L. MELONE.
